TELEVISION RECEIVER

Melvin H. Boldt, Glenview, Ill., assignor to Zenith Radio Corporation, a corporation of Delaware

Filed Dec. 4, 1959, Ser. No. 58,555

Term of patent 7 years

(Cl. D56—4)

FIG. 1

FIG. 2

FIG. 3

The dominant features of my design reside in those portions of the drawing shown by means of full lines.

I claim:

The ornamental design for a television receiver, substantially as shown and described.
